UNITED STATES PATENT OFFICE.

THOMAS DANQUARD, OF NEW YORK, N. Y., ASSIGNOR TO AUTOPIANO COMPANY, OF NEW YORK, N. Y., A CORPORATION OF NEW YORK.

MODULATING ATTACHMENT FOR AUTOMATIC MUSICAL INSTRUMENTS.

No. 871,788.

Specification of Letters Patent.

Patented Nov. 26, 1907.

Application filed July 24, 1905. Serial No. 270,935.

To all whom it may concern:

Be it known that I, THOMAS DANQUARD, a citizen of the United States, residing at New York, in the county of New York and State 5 of New York, have invented a new and useful Modulating Attachment for Automatic Musical Instruments, of which the following is a specification.

This invention relates to that class of musical instruments which are controlled by strips of perforated paper.

The especial object of this invention is to provide simple and efficient means for accenting the desired individual notes of a musical composition so as to produce modulated or accented effects.

In a prior patent granted to me May 30, 1905, No. 791,441, I have shown and claimed an improvement in automatic musical instruments by means of which I have been able to produce arpeggio or broken chord effects by "skewing" the tracker-board so that the same will stand at an oblique angle to the line of travel of the music sheet.

25 The especial object of my present invention is to utilize the "skew" attachment of the tracker-board for producing an accented effect for any desired notes of a musical composition.

30 In an automatic musical instrument constructed according to this invention, when the tracker-board occupies its normal position the striking devices of the instrument will be controlled in the same manner which is usual in instruments of this class.

35 The tracker-board is provided with one additional channel, and the music sheet has perforations which coöperate with the additional channel in such way as to permit the 40 accenting or loud striking of any one note of a desired chord which is played with broken or arpeggio effect.

In the accompanying two sheets of drawings, Figure 1 is a plan view showing the 45 tracker-board and winding rolls coöperating therewith. Fig. 2 is a transverse sectional view taken on the line 2-2 of Fig. 2 showing the tracker-board in tipped or "skew" position. Fig. 3 is a similar view showing the 50 tracker-board in the normal position occupied by it during ordinary playing. Fig. 4 is a similar view showing a modified form of construction in which the tracker-board is made of two separate pieces. Fig. 5 is a sectional 55 view illustrating the connections controlled

by the additional perforation of the tracker-board, and Fig. 6 is an enlarged plan view showing the tracker-board and music sheet lined or ruled to show the time of action of the marginal perforation so as to control any 60 desired note of a chord.

As shown more particularly in the first sheet of drawings, 10 designates the tracker-board which is provided with the usual tracker-board channels 11 and with a single 65 track-board channel 12 for securing accented effects. Coöperating with the tracker-board is a music sheet 13 which is unwound from a music roll 14 and wound up on the winding-roll 15. The music-roll 14 and winding roll 15 are controlled by any of the ordinary driving connections including a chain 16 for winding and rewinding the music-sheet.

The tracker-board, as in my previous patent before referred to, is mounted so that it can be set at an oblique angle with respect to the path of travel of the music sheet. In the present instance, the tracker-board as shown, is pivoted on the screw 18 in a lug 17 70 carried by the frame. At its opposite end the tracker-board 10 is mounted to swing on a lug 19 and is held in normal position by a spring 20. Coöperating with the tracker-board 10 is a cam 21 having a handle by 75 means of which the cam can be turned to throw the tracker-board back obliquely or in "skew" position.

The parts as thus far described may be substantially the same as shown in my previous patent before referred to except that the tracker-board is provided with the channel 12 in addition to the ordinary note channels 11.

When the entire tracker-board is bodily 95 movable and is connected to the action by rubber tubes, as shown in Figs. 2 and 3, the tracker-board channel 12 may have a nipple 24 which is normally seated against a valve 25 carried by an adjusting screw 27 100 threaded into a T-shaped head of a pipe or channel 28, and I prefer to employ such an arrangement as this so that when the tracker-board is in normal position, as shown in Fig. 3, the connection between the tracker-board 105 channel 12 and pipe 28 will be cut off, but when the tracker-board is shifted, the passage will be opened between the tracker-board channel 12 and the channel 28. In some cases, for example, when lead or other 110

non-flexible pipes are used, the tracker-board may be made in two separate pieces, as shown in Fig. 4, and when the tracker-board is in normal position the tracker-board channel 12 will normally stand out of line with the channel or passage 28.

The devices controlled from the pipe or passage 28 are illustrated most clearly in Fig. 5. As shown in this figure, the channel 10 or pipe 28 is connected to operate a primary pneumatic 30. Above the primary pneumatic 30 is a chamber connected by a pipe 31 to the main wind chamber or bellows. The primary pneumatic 30 is provided with 15 the ordinary small leak passage so that the parts will stand normally in the position shown in Fig. 5. When atmospheric pressure is admitted through the pipe 28 the valve-stem of the primary pneumatic 30 will be raised, closing the valve 32 and opening the valve 33. This will connect the passage 34 of the operating pneumatic 35 with the suction. Connected with the movable leaf of the pneumatic 35 is a valve-stem 20 which carries a valve 36 which normally closes the connection between the main wind-chest 37 and the main wind-trunk or pipe 38 which leads to the action.

When the instrument is to be played to 30 produce usual or non-accented effects, the suction from the main wind-chamber 37 to the main wind pipe 38 is controlled by a valve which is operated by the usual regulating pneumatic 39 to equalize or diminish 35 the air pressure under which the striking devices are operated. When, however, the valve 36 controlling the direct connection is open, any desired air pressure may act directly upon the striking devices to sound 40 notes with any desired striking force or loudness.

The coöperative relation of the music sheet with the tracker-board whereby the supplemental perforations enable the instrument to produce accented or modulated effects, is most clearly illustrated in Fig. 6. As shown in this figure, the music-sheet may be provided with a number of perforations P corresponding to the notes of a chord or 45 phrase of music. When the tracker-board is in normal position, the notes corresponding with any set of perforations P will be sounded simultaneously, but when the tracker-board is tipped or set to "skew" 50 position, the notes of the chord will be sounded with arpeggio or broken chord effect. Now, if it is desired to accent any one of the notes which are thus successively sounded, the music-sheet may be provided with a 55 corresponding perforation p which is cut in the music sheet in such position that immediately before the perforation corresponding with the note which it is desired to accent comes over the tracker-board, the controlling connections before described will oper- 60

ate to open the direct wind-way connection thus permitting the accenting of an individual note or any number of notes which are struck, while the supplemental channel of the tracker-board remains open. In the particular music sheet illustrated in Fig. 6, it will be noted that the last or treble note of the chord is the one which will be played with an accented or loud striking effect.

I am aware that numerous changes may be 75 made in applying my invention to different types of automatic musical instruments, and that many variations may be made in the devices which are controlled from the supplemental or accenting channel of the tracker- 80 board.

I do not wish, therefore, to be limited to the particular construction I have herein shown and described, but

What I do claim and desire to secure by 85 Letters Patent of the United States is:—

1. In an automatic musical instrument, the combination of a movable tracker having a series of channels and a supplemental channel, means for moving the tracker from normal position, and means whereby the supplemental channel is normally closed, but is opened when the tracker is moved from normal position.

2. In an automatic musical instrument, 95 the combination of a tracker having a series of channels and a supplemental channel, means for moving the tracker from normal position, and a valve which is closed when the tracker is in normal position for cutting 100 off the supplemental channel.

3. In an automatic musical instrument, the combination with the wind-chest, main wind-trunk, and action of a tracker having a series of channels and a supplemental channel, 105 means for closing the supplemental channel when the tracker is in normal position, a regulating device controlled from the supplemental channel and comprising a primary pneumatic, valves operable by the primary 110 pneumatic, an operating pneumatic controlled by said valves, and a shut-off valve controlled from said operating pneumatic and normally cutting off direct wind connection between the wind-chest and the main 115 wind-trunk leading to the action, but which is opened to provide direct wind connection for striking desired accented notes.

4. In an automatic musical instrument, 120 the combination of a tracker having a series of channels "skewed" relatively to the line of travel of the music sheet, and having a supplemental channel with regulating devices controlled from the supplemental channel to admit direct pressure for striking notes 125 which it is desired to accent.

5. In an automatic musical instrument, 130 the combination of a tracker having a series of channels "skewed" relatively to the line of travel of the music sheet, and having a

supplemental channel, a primary pneumatic controlled from the supplemental channel, and an operating pneumatic controlled from the primary pneumatic to open a direct wind-way connection for striking notes which it is desired to accent.

6. In an automatic musical instrument, the combination of a tracker having tracker-board channels normally at right angles to the line of travel of the music-sheet and a supplemental channel, means for "skewing" the tracker, and means for closing the supplemental tracker-board channel except when the tracker-board is in "skewed" position.

7. In an automatic musical instrument, the combination of a tracker having tracker-board channels normally at right angles with the line of travel of the music sheet and having a supplemental tracker-board channel, means for "skewing" the tracker, and a normally closed valve cutting off the supplemental tracker-board channel except when the tracker occupies its "skewed" position.

8. In an automatic musical instrument, the combination of a tracker having a line of a series of channels normally at right angles to the line of travel of the music sheet and having a supplemental tracker-board channel, means for closing the supplemental channel except when the tracker-board occupies a "skewed" position, a regulating device controlled from the supplemental channel and comprising a primary pneumatic, valves operated by the primary pneumatic, an operating pneumatic controlled by said valves, and a shut-off valve controlled from said operating pneumatic and normally cutting-off direct wind connection between the wind-chest and the main wind-trunk leading to the action, but which is opened to provide direct wind connection for striking desired accented notes.

9. In a musical instrument, the combination with the wind-chest, main wind-trunk, and action of a tracker having a series of channels and a supplemental channel, means for closing the supplemental channel, a regulating device controlled from the supplemental channel, an operating pneumatic controlled by said regulating device, and a

shut-off valve controlled from said operating pneumatic and normally cutting off the direct connection between the wind chest and the main wind trunk leading to the action, but which is opened to provide direct wind connection for striking desired accented notes.

10. In a musical instrument, the combination of a movable tracker having a series of channels and a supplemental channel, an operating pneumatic controlled from the supplemental channel, means operated by said pneumatic to open a direct wind-way connection, and means whereby the supplemental channel is normally closed, but is opened when the tracker is moved from normal position.

11. In an automatic musical instrument, the combination of a movable tracker having a series of channels and a supplemental channel, means for moving the tracker, means whereby the supplemental channel is normally closed, but is opened when the tracker is moved to a certain position, and a regulating device controlled from the supplemental channel to admit direct pressure for striking notes which it is desired to accent.

12. A musical instrument having means for modifying notes, and a tracker having a series of channels and a supplemental channel adapted to be located in rear of the series of channels relative to the movement of the note sheet and connected with the modifying means for controlling the operation thereof.

13. A musical instrument having a tracker provided with a series of channels and a supplemental channel adapted to be located in rear of the series of channels relative to the movement of the note sheet, and having connections for modifying the sounding of notes whereby the modifying connections will be operated before the note to be modified is sounded.

In testimony whereof I have hereunto set my hand, in the presence of two subscribing witnesses.

THOMAS DANQUARD.
